UNITED STATES PATENT OFFICE.

WILLIAM E. WINE, OF TOLEDO, OHIO.

DOOR MECHANISM FOR RAILWAY CARS.

Application filed February 18, 1922. Serial No. 537,38.

To all whom it may concern:

Be it known that I, WILLIAM E. WINE, a citizen of the United States, residing at Toledo, in the county of Lucas and State of Ohio, have invented certain new and useful Improvements in Door Mechanisms for Railway Cars, of which the following is a specification.

This invention relates to door mechanisms for railway cars or the like and has among its objects to provide a simple form of door securing means which will be economical of cost and of sufficiently sturdy construction to meet the conditions of the service in which it will be used. A further object of the invention is to provide a simple and convenient form of door securing mechanism for use with a door having a sealing flange formed along one or more of its edges.

With such general objects in view, the invention consists of the formation, combination and arrangement of parts as will be herein described and particularly pointed out in the appended claim.

In the drawings, which show a preferred embodiment of the invention, Figure 1 is a fragmentary side elevational view of the lower end of the hopper of an ordinary twin hopper coal car of the type in general use in railroad service. In this view is shown a door mechanism constructed in accordance with the principles of the present invention. Figure 2 is a fragmentary and elevational view of the same corner of the car as shown in Figure 1. Figure 3 is a transverse sectional view taken through the door securing mechanism, approximately on the line 3—3 of Figure 1. Figure 4 is a transverse sectional view taken through a portion of the hopper and the door mechanism approximately on the line 4—4 of Figure 1. The approximate plane of this section is also denoted by the line A—A of Figure 2. Figure 5 is a diagrammatical view indicating the type of car to which the present invention is shown as applied in the preceding figures, the view being in side elevation, and the arrangement of the doors being indicated. Figure 6 is a detached view, in diagram, of a pair of doors as ordinarily used in twin hopper car construction, the center sills of the car also being indicated in this figure, in order to show their relationship.

Referring now to these drawings, it will be noted that the style of car to which the invention is shown as applied is of the twin

hopper type, having sides 1 and bottom slope sheets 2. Near the center of the car, the slope sheets terminate so as to form, with the adjacent portions of the sides of the car, a pair of hoppers, with their discharge openings turned toward each other, as indicated in the diagram of Figure 5. The center sills 3 of the car, which extend longitudinally of the same, ordinarily cut each of these hoppers into two portions arranged side by side. Doors such as 4 are arranged in pairs, are hinged end to end in order to close the discharge openings, door hinges for the same being indicated at 5 in Figures 5 and 6.

It is generally permissible that the doors for both of the hoppers at one end of the car may be operated in unison, and in view of this, it is preferred to connect the adjacent pair of doors at an end of the car by means of a flanged stiffening member 6, which extends transversely of the car from side to side. To this stiffening member both of the doors are secured as by means of the rivets 7, so that the doors are held in a definite spaced relationship by means of these stiffeners. The stiffener is preferably formed of a length of bulb angle iron having one flange thereof lying against the plates of the doors, and the other flange outstanding from the door plates. This stiffener is preferably of greater length than the width of the car, so that the ends of the stiffener extend slightly beyond the line of the car sides.

Secured to each side of the car adjacent the ends of the stiffener 6 is a door securing hook 8, which is pivotally connected to the car side. This pivoting is effected through the medium of a bracket 9, which lies against the side of the car, the bracket having suitable spools or bosses 10 provided upon its outer face, upon one of which the pivoted end of the hook 8 is positioned. The hook 8 is provided with a locking face 11, which is arranged to seat behind the flange 10 of angle 6, this being the flange thereof heretofore described as lying directly against the outer face of the door plates. The hook 8 is also provided with an approach portion 11, so arranged that when the door is pushed shut by means of the hand or the foot of the attendant, the hook will be automatically lifted by the movement of the door, and will then drop into locking position, as shown in Figure 1.

In order to prevent the accidental dis-

placement of the hook, an eccentric cam 12 is also mounted upon another of the bosses 13 on the bracket 9, adjacent the back of the hook 8. This cam may be rotated about this 5 boss as a center into contact with the back of the hook to thereby forcibly hold the hook in engagement with the door angle. A plate 15 overlies the hook and the cam, and rests upon the tops of the bosses 13, a space being 10 thereby formed between this plate and the bracket 9 for the free operation of the hook and the cam. Securing rivets such as 16 pass through pierced openings through the centers of the bosses and through registered 15 openings in the plate 15 and the car side 1, thereby securing all of the parts together. An additional rivet such as 17 may pass directly through registered openings in the plate 15, the bracket 9 and the car side 1, 20 for additional securing purposes.

It will be noted that the bracket 9 is so constructed as to space the inner face of the hook slightly away from the car side 1, providing an interval such as 18 between these 25 two parts. This space is provided in order to accommodate the edge of the door plate, which is turned at right angles to the general plane of the door to form the sealing flange 19, extending around and overlapping 30 the edge of the side plate of the car, thereby forming an effective seal against loss of lading such as fine coal. A flange 20 may be similarly provided along the bottom edge of

this door plate for sealing the joint between the door plate and the edge of the chute plate 2. A stiffening angle such as 21 may also be secured to the chute plate, if desired.

The door arrangement thus described constitutes an effective means for preventing loss of lading either by imperfectly fitting doors or by improperly closed doors. The arrangement is furthermore such that the parts can all be constructed of sturdy form and of exceedingly low first cost.

I have thus described an embodiment of my invention. Other embodiments are possible within the scope of the appended claim without departing from the spirit thereof.

What is claimed is:

A door mechanism for railway cars including a door hinged to the car body, the same having one of its edges lying along the line of a side of the car, a stiffening member attached to the door and extending beyond the said edge thereof and beyond the line of the adjacent side of the car, a door securing hook pivoted upon the said side of the car and arranged for engaging cooperation with the said stiffening member, the said hook being spaced slightly away from the said side of the car, and the door being provided with a sealing flange arranged to slightly overlie the said side of the car and to occupy a position between the same and the said hook.

In testimony whereof I affix my signature. 65
WILLIAM E. WINE.
